UNITED STATES PATENT OFFICE.

RICHARD V. WESTLIN, OF FITCHBURG, MASSACHUSETTS.

ADJUSTABLE GAS-BURNER.

1,307,226.

Specification of Letters Patent. Patented June 17, 1919.

Application filed January 11, 1919. Serial No. 270,692.

To all whom it may concern:

Be it known that I, RICHARD V. WESTLIN, a citizen of Russia, residing at Fitchburg, in the county of Worcester and State of Massachusetts, have invented certain new and useful Improvements in Adjustable Gas-Burners, of which the following is a specification.

My invention relates to burners for gas stoves, and more specifically to that class of burners having means for regulating the area of the flame surface.

My object is to provide a device of this character adapted to be easily applied to the burner of a gas stove, and affording means for regulating the diameter of the flame surface of the burner to suit vessels of varying sizes from large to small; and thus avoiding waste of gas.

Minor objects will appear in the subjoined description.

An important feature of my invention consists of a plate adapted to lie in flat engagement with the top of an ordinary stove burner and to rotate thereon, and provided with series of perforations adapted to come successively into registration with the perforations in the burner as the plate is rotated to different positions thereon.

The invention consists in the novel construction and arrangement of the several parts, as will be hereinafter described and claimed, reference being had to the accompanying drawings in which:—

Figure 1 is a top plan view of my improved burner.

Fig. 2 is a transverse vertical section taken centrally through Fig. 1 with the grate omitted.

Fig. 3 is a top plan view of the revolving plate, on an enlarged scale; and,

Fig. 4 is a transverse vertical section of Fig. 3.

The letter A indicates an ordinary burner, as a whole; this burner being provided with the usual star-shaped burner proper B, shown in dotted lines in Fig. 1.

The arms of the star-shaped burner B are provided with radial rows of openings B¹, the corresponding openings of the respective arms all being respectively equidistant from the center of the burner.

The circular plate 1 is provided at its center with a pipe 2.

This plate 1 rests on top of the star-shaped burner B in flat engagement therewith, and the pipe 2 extends down through the central opening B² of the burner.

The plate is provided with a plurality of openings or perforations arranged in concentric-and-radial series, and for convenience of reference in considering these perforations, in their concentric relation they are indicated by 1^a, 2^a, 3^a and 4^a, while in their radial relation they are arranged in a number of similar groups, each group consisting of perforations indicated by 1^b, 2^b, 3^b and 4^b.

The plate 1 has a concentric slot 3 near its periphery, into which slot is received a pin 4 extending upwardly from the burner. The plate 1 is also provided with a radial hand or pointer 5, and a segmental rack 6. The rack 6 is engaged by a cog wheel 7 on the inner end of a spindle 8; said spindle being suitably mounted to rotate in the device, and being provided on its outer end with a thumb-and-finger wheel preferably fluted or corrugated on its periphery.

The different series of openings in the plate 1 are arranged to successively come into registration with the openings B¹ of the burner proper as the plate 1 is rotated.

The pipe 2 extending downwardly from the plate 1 through the central opening B² of the burner forms an axle of rotation for the plate. This pipe projects down a sufficient distance below the under side of the burner to receive the spring 10. Immediately above the spring and borne upwardly thereby against the under side of the burner is a washer 11 loosely fitting the pipe-axle 2, while at the lower end of the pipe 2 is another washer or bolt 12 rigidly secured thereto in any preferred manner when the parts are assembled. From this arrangement it will be seen that the spring 10 serves to reliably hold the plate 2 in close engagement with the top of the burner. If preferred the lower end of the pipe 2 may be threaded, and the nut or washer 12 provided with coöperating threads, in which case the tension on the spring 10 may be adjusted.

On the periphery of my burner I have provided the numerals 1, 2, 3, and 4, and these numerals are so arranged and spaced from each other relatively to the perforations in the burner and plate (radially considered), and to the hand 5, that when the plate is rotated to bring the hand to point, say at 4, all four of the several radial series of openings 4^b of the plate will be brought into registration with the several radial series of openings B¹ of the star-shaped

burner. When the hand 5 points at 3, the several radial series of openings 3^b of the plate will be in registration with their corresponding openings in the star-shaped burner; 5 but it will be observed that while each radial series of openings 4^b is composed of one opening from each of the four concentric series of openings (1^a, 2^a, 3^a, and 4^a), the radial series 3^b are likewise composed 10 of openings from only three of the concentric series; and it will be further seen that when the hand 5 points at 2, only openings in the concentric series 1^a and 2^a will be in registration with the corresponding openings of the star-shaped burner B; and likewise, when the hand points at 1, only the inner circle 1^a of the openings in the plate will be in registration with the corresponding openings B^a of the burner B. From 15 this it will be seen that the area of flame surface of my burner may be increased or diminished at the pleasure of the operator, so that the same burner may be used for any sized vessel from a large pot or pan 20 down to a tin cup or bowl, without wasting gas at any time, or having the flame going up around the sides of the bowl or small vessel and burning or scorching the contents around the sides. 25 30 The stop 4 working in the slot 3 prevents the plate 1 from rotating a sufficient distance to permit the rack 6 to move out of engagement with the cog wheel 7; but if the rack 6 be extended all around the plate 1, 35 the slot 3 and the stop 4 can be dispensed with.

As to the operation of my device it need only be said in addition to the foregoing, that when a very small area of flame is desired, the plate 1 is revolved forwardly by the finger wheel 9 till the hand 5 points at the numeral 1 on the periphery of the burner, then gas can only escape through the inner circle 1^a of the concentric openings. 40 45 When the hand 5 is brought to point at 2, the two inner circles 1^a and 2^a will be in use; and so on.

It will be noticed that the pipe 2, being open at its top and bottom, leaves the burner 50 provided with a central air-opening as usual with ordinary burners.

Having now described my invention, what I claim as new and desire to secure by Letters Patent is:—

55 1. In a device of the character described, a burner having its flame surface disposed in a curvilinear plane and provided with perforations arranged in concentric and radial series for the escape of fuel; a curvilinear plate adapted to lie in flat engagement with the surface of the burner and to rotate thereon, and having perforations corresponding in number and relative posi-

tion to those of the burner, whereby all the openings in the burner may be uncovered at 65 one time; said plate also having additional perforations arranged to form additional radial rows of openings; the radial rows thus formed by said additional perforations having successively less openings than the 70 number of perforations in the radial rows of perforations in the burner.

2. In a device of the character described, a burner having its flame surface disposed in a curvilinear plane and provided with 75 perforations arranged in concentric series for the escape of fuel; a curvilinear plate adapted to lie in flat engagement with the surface of the burner and to rotate thereon, and having perforations corresponding to 80 those of the burner, said plate also having additional perforations arranged to successively come into registration with the perforations of the burner when the plate is rotated thereon, openings in the burner and plate being arranged to come into registration with each other in increasing numbers when the plate is rotated in one and in decreasing numbers when the plate is rotated 85 in the other direction. 90

3. In a device of the character described, a burner having its flame surface disposed in a plane and provided with perforations for the escape of the fuel, said perforations being arranged in concentric and radial 95 series; a rotatable plate adapted to lie in flat engagement with the burner and also provided with perforations arranged in concentric-and-radial series and adapted to come into registration with the perforations 100 of the burner as the plate is rotated thereon, said coöperating perforations of the burner and plate being arranged to increase the flame area of the burner when the plate is rotated in one direction and to decrease it 105 when the plate is rotated in the other direction; and means for manually controlling the plate. 110

4. In a device of the character described, a burner having a flat curvilinear flame surface with an opening for a draft of air at the center of said flame surface; a rotatable plate having at its center a hollow axle extending downwardly through the central opening of the burner to a point below the burner; a spring mounted on the lower end of said axle and arranged to hold the plate in close engagement with the burner, said burner and plate having perforations adapted to coöperate with each other and arranged to give varying areas of flame surface according to the rotatable position of the plate relatively to the burner. 115 120

In testimony whereof I affix my signature

RICHARD V. WESTLIN.
